CLAIM

I claim the ornamental design for an insulation support channel, as shown and described.

DESCRIPTION

FIG. 1 is a front elevation view of an insulation support channel showing my new design.

FIG. 2 is a side elevation view thereof.

FIG. 3 is a top plan view thereof.

FIG. 4 is a bottom plan view thereof; and,

FIG. 5 is a perspective view thereof.

The insulation support channel is shown with a symbolic break in its length. The appearance of any portion of the insulation support channel between the break lines forms no part of the claimed design.
